MANICURING IMPLEMENT

Earl S. Tupper, Smithfield, R. I.

Application October 25, 1956, Serial No. 43,530

Term of patent 14 years

(Cl. D86—10)

I claim:

The ornamental design for a manicuring implement, as shown.
